FILTER FOR PRESSURIZED FLUID

John Joseph Humphrey, Denver, Colo., assignor to C. A. Norgren Co., Littleton, Colo.

Filed July 17, 1972, Ser. No. 272,165

Term of patent 14 years

Int. Cl. D23—01

U.S. Cl. D23—4

FIG. 1 is a perspective view of a filter for pressurized fluid showing my new design;

FIG. 2 is a side elevational view thereof;

FIG. 3 is an additional side elevational view thereof;

FIG. 4 is a top view thereof; and

FIG. 5 is a bottom view thereof.

I claim:

The ornamental design for a filter for pressurized fluid, as shown.
